CLAIM

The ornamental design for an auscultatory tube for stethoscope, as shown and described.

DESCRIPTION

FIG. 1 is a front and top perspective view of an auscultatory tube for stethoscope in accordance with my new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; and, FIG. 7 is a bottom plan view thereof.

The broken lines in the figures are for the purpose of showing environmental structure and form no part of the claimed design.
